CLAIM

The ornamental design for an outdoor storage cabinet, as shown and described.

DESCRIPTION

FIG. 1 is a perspective view of an outdoor storage cabinet showing my new design;

FIG. 2 is a front elevational view thereof;

FIG. 3 is a rear elevational view thereof;

FIG. 4 is a right side elevational view thereof, with the left side elevational view being a mirror image thereof; and,

FIG. 5 is a top plan view thereof, and with no ornamentation being claimed for the bottom plan thereof.
